UNITED STATES PATENT OFFICE.

BENJAMIN I. MOTT, OF BROOKLYN, NEW YORK.

DESIGN FOR A BOTTLE.

SPECIFICATION forming part of Design No. 18,495, dated July 31, 1888.

Application filed June 9, 1888. Serial No. 276,638. Term of patent 7 years.

To all whom it may concern:

Be it known that I, BENJAMIN I. MOTT, a citizen of the United States, residing at Brooklyn, in the county of Kings and State of New York, have invented and produced a new and original Design for Bottles; and I do declare the following to be a full, clear, and exact description of the same, reference being had to the accompanying drawings, forming a part thereof.

Figure 1 illustrates a side view of a bottle embodying my invention. Fig. 2 illustrates a view of the bottle as seen from the bottom.

The leading features of my design consist in a substantially square bottom to the bottle having rounded corners, and as the sides of the bottle rise the square form of the bottom is gradually lost, each successive horizontal cross-section of the bottle from the bottom up assuming more and more a circular form, until at or near the shoulder of the bottle, *a*, its cross-section is a circle, and from the shoulder

the sides of the bottle all tumble into the neck by equal inward and upward curves, so that cross-sections of the bottle between the shoulder *a* and the neck are all of them circles, but of differing diameters. 25

What I claim is—

The design for a bottle herein shown and described, the same consisting of a bottle having a substantially square bottom with rounded corners, the sides whereof, as they rise toward the neck, assuming more and more a circular form until at or near the shoulder *a* of the bottle it is circular in form, from which point 30 the sides tumble into the neck of the bottle by equal inward and upward curves, as set forth. 35

In testimony whereof I affix my signature in presence of two witnesses.

BENJ. I. MOTT.
